UNITED STATES PATENT OFFICE.

WILLARD F. MEYERS, OF LONG ISLAND CITY, NEW YORK.

STONE AND METAL SHAPING MACHINE.

987,390.

Specification of Letters Patent. Patented Mar. 21, 1911.

Application filed September 17, 1908. Serial No. 453,408.

To all whom it may concern:

Be it known that I, WILLARD F. MEYERS, a citizen of the United States, residing at Long Island City, borough of Queens, in the county of Queens and State of New York, have invented a certain new and useful Improvement in Stone and Metal Shaping Machines, of which the following is a specification, reference being had therein to the accompanying drawings, forming part thereof.

My invention relates generally to machines for shaping stone and metal and relates more particularly to molding and coping machines, and has for its objects the shaping of stones of various sizes to a great variety of shapes or forms and particularly the shaping or forming of stone moldings for buildings and the like, and also the dressing of metal surfaces of various configurations and curvatures, particularly extremely flat curves or curves of very long radii, and has as further objects facility of adjustment and setting up the work and minimizing of the time required in adjusting the machine and setting up the work, and to these ends my invention includes means for imparting a plurality of feed movements to the tool and to the work, including rectilinear and curvilinear feed movements, and means for combining the different feed movements to produce desired resultant feed movements.

My invention also includes other advantageous features and details of construction, as will hereinafter appear.

Figure 1 is a plan view, partly in section and with parts broken away, of a machine embodying my invention. Fig. 2 is a side elevation, partly broken away. Fig. 3 is a section on planes indicated by the line III—III of Fig. 1 as viewed from the right. Fig. 4 is an end elevation, partly in section. Fig. 5 is a detail plan showing the platen or surface plate and the table, with portions broken away. Fig. 6 is a section on a plane indicated by the line VI—VI of Fig. 5 looking upward. Fig. 7 is an enlarged elevation of the tool carrier or tool carriage as viewed from the rear or reverse side of Figs. 2 and 3, and as viewed from the left of Figs. 4 and 8, portions of the swinging arm being also shown. Fig. 8 is an enlarged transverse vertical section of the tool carrier and swinging arm or frame on a plane indicated by the line VIII—VIII of Figs. 1, 2 and 3, look-

ing upward in Fig. 1 and as viewed from the left in Figs. 2 and 3. Fig. 9 is a horizontal section on planes indicated by the line IX—IX of Fig. 8 looking downward. Fig. 10 is an enlarged vertical section of a portion of the feed mechanism for the tool carriage taken on a plane indicated by the line X—X of Figs. 1 and 4 as viewed from the right. Fig. 11 is an enlarged vertical section of the feed reversing mechanism for the tool carriage on a plane indicated by the line XI—XI of Fig. 1, this feed reversing mechanism appearing in elevation in Figs. 2 and 3. Fig. 12 is an elevation of a modified tool support adapted for carrying a planer instead of a grinder, portions of the swinging arm also being shown. Figs. 13, 14 and 15 are diagrams illustrating some of the various shapes to which stones may be formed with the machine of the present invention.

The embodiment of the invention illustrated in Figs. 1 to 11, inclusive, comprises a tool-supporting carriage having both rectilinear and curvilinear feed movements and a work support having both rectilinear and rotary feed movements, with means for forming a variety of combinations of the different feed movements to produce different resultant feed movements at will.

The work support comprises a surface plate or platen 1 supported by a table 2 and mounted to rotate in horizontal planes, the table 2 being of hollow or shell structure and the platen 1 having a central boss 4 extending through a slot in the top plate of the table. The table 2 is supported by a bed 5 and is mounted to slide laterally in V-guides or ways 7 formed in the bed and into which fit guide rails 12 formed on the table. Means are provided for feeding the table along the ways, and also for rotatively feeding the platen relatively to the table. Also means are provided for adjusting the platen horizontally on the table in a direction at right angles to the lateral feed movement of the table, for adjusting the table to different positions along the ways, and for adjusting the platen to different rotative positions on the table.

To impart a rotative feed movement to the platen, a stub shaft 13, journaled in a bearing 14, has a squared end fitting into the central boss 4 of the platen. A worm wheel 15, fixed on the stub 13, is engaged by a worm 16 splined on an actuating shaft 17 journaled in the table 2. The splined con-

nection of the worm 16 with its shaft 17 permits the rotative feeding of the platen without regard to the sliding adjustment of the platen on the table, and the worm 16 is held in engagement with worm gear 15 by brackets 18 extending from the bearing 14.

The actuating shaft 17 is adapted to be driven by a parallel shaft 19, also journaled in the table 2, and having fixed thereon a spur gear 20 meshing with a gear 21 loose on the actuating shaft 17. The gear 21 is adapted to be connected with the actuating shaft 17 by an ordinary tooth clutch 22 controlled by a hand lever 23 (Figs. 3 and 4). The rotational feed of the platen may be stopped by throwing out the clutch 22, and when this clutch is out or in non-operative position the platen may be rotatively adjusted by manually rotating the actuating shaft 17, which is provided with a squared end at 24 for the attachment of an ordinary crank. The parallel shaft 19 carries a bevel gear 25 which engages two bevel gears 26 and 27 shown as formed integral respectively with flanged sleeves 28 and 29 journaled in brackets 30 on the table 2 and loosely mounted on a counter shaft 31. A tooth clutch 32 of ordinary form, controlled by a hand lever 33, is arranged between the gears 26 and 27 so as to engage them alternately with the counter shaft 31, so that the parallel shaft 19 may be driven in either direction for reversing the direction of rotational feed of the platen 1, or may be at rest when the clutch 32 is in its median position. The reversing clutch 32 is splined on the counter shaft 31, as shown, so that the rotational feed movement may be communicated to the platen without regard to the horizontal movement of the table 2 along the ways 7.

To effect the sliding horizontal adjustment of the platen 1 on the table 2, the bearing 14 for the stub shaft 13 is mounted to slide in a slot 34 (Fig. 5) provided in the lower plate or part of the table, and the worm-retaining brackets 18 extend upward through a similar parallel slot 35. Two parallel adjusting screws 36, one at each side 50 of the stub shaft 13, are journaled in the table 2 and have screw-threaded engagement with the bearing 14 to adjust it along the slot 34 and thereby to effect a corresponding adjustment of the platen relatively to the table. The screws 36 carry gears 37 and 55 may be concurrently actuated by an intermediate gear 38 carried on a squared shaft 39 for the attachment of an ordinary crank by which the adjustment may be effected at will.

The platen or work support 1 is given a rectilinear feed movement by feeding the table 2 along the ways 7. This feed movement is effected by a spur gear 40 engaging 65 with a stationary rack 41 formed in the bed

5, and the gear 40 is fixed on a short shaft 42 journaled in the table 2. The table 2, carrying with it the platen 1, may be fed in either lateral direction at will by ordinary tumbler gears 43 forming a connection between the gear 21 and a spur gear 44 fixed on the shaft 42. The tumbler gears are carried by a two-armed rockable frame 45 pivoted on the outer end of the short shaft 42 and rockable to three positions, in any one of which it may be held by a spring pin 46 engageable in corresponding holes in the end of the table 2 as shown. When the pin 46 is in the middle hole, as shown in the drawings (Fig. 4), the short shaft 42 will be rotated to feed the table along the ways in one direction of movement; when the pin is in the hole at the right, the shaft 42 will be given an opposite rotation to feed the table in the opposite direction; and when the pin is placed in the hole at the left, the tumbler gears will be disconnected from the gear 21 and the shaft 42 will remain at rest and the table will not be fed but will remain stationary. When the tumbler gears are thus disconnected from the gear 21, the table may be adjusted to different positions along the ways, and to effect this adjustment an adjusting shaft 47 (Fig. 3) is journaled in the bed 5 and carries a spur gear 48 which engages a rack 49 formed on the bottom or lower side of the table 2, the shaft 47 being provided with a squared end as shown for the reception of a crank. The platen 1 is shown as provided on its upper side with T-grooves 50 to permit of the work being secured in place by ordinary clamps, and a usual drainage channel 51 extends around the edge of the platen.

The tools shown as supported or carried on the tool carriage or tool carrier 52 are 105 a rotary grinder 53 and a jointing saw 54. The grinder 53 is for dressing or shaping the edges of the stone and the jointing saw 54 is for cutting the stone along straight lines. The grinder 53 110 is formed of abrasive material, as indicated in the drawings, and the jointing saw 54 is shown as formed of abrasive material the same as the grinder 53, but, so far as the present invention is concerned, it is of no 115 consequence what kind of saw blade is employed or of what material it is composed. In fact, one kind of saw blade could be substituted for another in the same machine.

The grinder 53 is mounted on a vertical 120 shaft 55 journaled in a shaft hanger or shaft bearing 56 vertically adjustable in guides or ways 57 formed on the carriage 52, the shaft 55 being provided with collars 58 so that the shaft and grinder are vertically adjustable 125 with the shaft hanger 56. To effect this adjustment a vertical screw 59 is journaled in bearings on the carriage as shown and has screw-threaded engagement with an extension 60 from the shaft hanger, and is ar- 130

ranged to be actuated by bevel gears 61 and a hand wheel 62.

To actuate the grinder 53 a spur gear 63 is provided and is shown as formed integral with a flanged sleeve 64 journaled in a bearing 65 fixed on the carriage. The shaft 55 passes loosely through the sleeve 64 and a tooth clutch 66, controlled by a hand lever 146 (Figs. 1, 2 and 3), is splined on the 10 shaft 55, so as to permit actuation of the grinder 53 without regard to its vertical adjustment relatively to the carriage, and is adapted to connect the gear 63 with the grinder shaft 55 and to disconnect it therefrom at will. The gear 63 is rotated by a spur gear 67 (Fig. 8) mounted on the top of the carriage 52 and formed integral with a bevel gear 68, which, in turn, is engaged by a bevel gear 69 provided with a flanged 15 sleeve 70 journaled in a bracket 71 on the carriage and splined on a longitudinally arranged driving shaft 72, as shown, so as to permit actuation of the gear 67, and consequently of the grinder, without regard to the 20 rectilinear adjustment of feeding movement of the carriage longitudinally to the shaft 72.

The jointing saw 54 is mounted on a short horizontal shaft 73 journaled in an L-shaped shaft hanger 74 vertically adjustable in 25 guides or ways 75 formed on the carriage 52, the jointing saw and its shaft, of course, partaking of this adjustment. To effect this adjustment a vertical screw 76 (Fig. 7) is journaled in bearings on the carriage as 30 shown and has screw-threaded engagement with an extension or bracket arm 77 secured to the shaft hanger 74, and is arranged to be actuated by bevel gears 78 and a hand wheel 79. To actuate the jointing saw, the jointing saw shaft 73 is provided with a bevel gear 80 engaged by a bevel gear 81 on a vertical shaft 82 journaled in a bearing on the shaft hanger 74 and passing upward loosely through a flanged sleeve 83 journaled 35 in a portion of the carriage 52. The sleeve 83 carries a spur gear 84 which is connected by an idler 85 with the grinder-actuating gear 67, above noted, so that the jointing saw actuating gear 84 is rotated from the driving shaft 72. The gear 84 may be engaged with the shaft 82 to rotate the same by an ordinary tooth clutch 86 controlled by a hand lever 87 (Figs. 1 and 7), the clutch 86 being splined on the shaft 82, as shown, to permit 40 actuation of the jointing saw without regard to its vertical adjustment relatively to the carriage.

It is evident that by manipulating the clutches 66 and 86, either the grinder 53 or the jointing saw 54 may be actuated from the driving shaft 72, or both the grinder and the jointing saw can be actuated at once should any contingency arise in which both could be employed, while manipulation of 45 the hand wheels 62 and 79 gives vertical ad-

justment of the grinder and of the jointing saw relatively to the work supported on the platen 1. Whichever of these tools (the grinder and the jointing saw) is not in use is adjusted to its highest position out of 50 the way of the operation of the other, and in the drawings both of these tools are shown as elevated to their highest positions relatively to the carriage 52.

The carriage 52, together with the tools 55 carried thereby, is arranged to have both a rectilinear and a curvilinear horizontal feed movement. To permit of these movements the carriage 52 is mounted to slide longitudinally on a horizontally arranged arm or 60 frame 88 which is adapted to swing laterally or horizontally as a whole, the sliding movement of the carriage on the arm permitting the rectilinear feed movement of the carriage and the swinging movement of the arm permitting the curvilinear feed movement of the carriage. To accurately guide the carriage 52 in its rectilinear movements, the carriage is provided with dove-tail gibbs which 65 engage with dove-tail ways on the arm 88, 90 as shown in the drawings.

To feed the carriage 52 along the ways longitudinally of the arm 88 a feed screw 89 is journaled at its ends in the arm 88, extending substantially from end to end of 95 such arm, and has a screw-threaded engagement with a nut 90 on the carriage (Fig. 8). A screw-actuating pinion 91 is loosely mounted on the end of the feed screw 89 and is adapted to be engaged or connected with 100 such feed screw and disconnected therefrom by an ordinary tooth clutch 92 controlled by a hand lever 93. The pinion 91 is engaged by a spur gear 94 fixed on a stub shaft 95 journaled in bearings on the frame or arm 105 88 as shown. Two bevel pinions 96 and 97 are loosely mounted on the stub shaft 95 between its bearings and are rotated in opposite directions by a bevel gear 98 carried on the lower end of a long vertical sleeve 99 110 journaled on the frame or arm 88. A tooth clutch 100 of ordinary form, controlled by a hand lever 101 (Fig. 2), is arranged between the pinions 96 and 97 so as to engage them alternately with the shaft 95, so that this 115 shaft may be driven in either direction to feed the carriage in either direction along the ways. The feed of the carriage may be stopped either by placing the clutch 100 in its median position or by disengaging the clutch 92, at the end of the screw 89. The stub shaft 95, outward from the gear 94, is provided with a squared portion as shown for the attachment of a crank to adjust the carriage along the ways independently of 120 its feed movement, the clutch 92 then being engaged and the clutch 100 being disengaged or in its median position so as to leave the shaft 95 free. The sleeve 99 is rotated by a worm wheel 102 fixed thereon and en- 125 130

gaged by a worm 103 carried by the driving shaft 72.

To permit swinging or curvilinear feed movement of the tool carriage the frame or arm 88 is pivoted at one of its ends on a supporting yoke or bracket 104 and is guided and supported at its other end by a curved or arcuate guide rail 105. To impart the swinging feed movement of the arm 88 the guide rail 105 is provided with a rack 106 engaged by a gear 107 fixed on a shaft 108 journaled in the long vertical sleeve 99. The gear 107 and shaft 108 are adapted to be engaged with the sleeve 99 to be rotated thereby by an ordinary tooth clutch 109 controlled by a hand lever 110 (Fig. 2). The sleeve 99, as above noted, is rotated from the driving shaft 72 by a worm 103 and worm wheel 102. The driving shaft 72 is arranged to be driven by a vertical main shaft 111 concentric with the pivot of the swinging arm or frame 88. The main shaft 111 passes loosely through two bevel gears 112 and 113 shown as formed integral with flanged sleeves journaled on the arm 88, and the gears 112 and 113 both engage a bevel gear 114 fixed on the adjacent end of the driving shaft 72. A tooth clutch 115 of ordinary form is arranged between the gears 112 and 113 so as to engage them alternately with the main shaft 111 to rotate the shaft 72 in either direction and thereby impart a swinging or curvilinear feed movement to the carriage in one direction or the other as desired. The driving shaft 72 will be at rest when the clutch 115 occupies a median position. This clutch is controlled by a hand lever 116. The clutch 115 is splined on the main shaft 111 as shown to permit actuation of the driving shaft 72 regardless of vertical adjustment of the arm 88. It is evident that when the driving shaft 72 is at rest the grinder 53 and the jointing saw 54 will be at rest and also that no feed of the carriage 52, either rectilinear or curvilinear, can take place. The main shaft 111 is also connected to the counter shaft 31, to furnish power for effecting the above described feed movements to the platen 1. A worm 117 carried by the main shaft 111 engages a worm wheel 118 fixed on a cross-shaft 119 carrying a gear 120 meshing with a gear 121 fixed on the counter shaft 31. The main shaft 111 may be driven from any convenient source of power by means of a belt pulley 122.

To enable the jointing saw 54 to cut a true radial surface relatively to the swinging arm 88 the face of the saw 54 adjacent to such cut face must lie in the same plane as the axis of the pivot of the swinging arm 88, and it is evident that to cut true radial faces at opposite ends of the work, for example, as indicated in Fig. 14, the saw 54 must be adjusted laterally a distance equal to the thickness of the saw. To effect this

adjustment a washer 147 is provided which may be placed on the shaft 73 at either side of the saw 54 to bring either face of the saw into the desired alignment, the washer being of the same thickness as the saw. 70

To accommodate work of different thicknesses, the arm or frame 88 may be adjusted vertically or raised and lowered. To permit of this adjustment the yoke or support 104 is mounted to slide on a column or post 123, and the ends of the curved guide 105 are supported on hollow legs 124 telescoping into hollow posts or columns 125. To effect this adjustment a lifting screw 126, journaled on the column 123, engages an elevating nut 127 on the yoke 104, and vertical shafts 128 within the posts 125 carry lifting worms 129 engaging elevating racks 130 in the hollow legs 124. The vertical shafts 128 are connected together to be actuated in unison by a transverse connecting shaft 131 (Figs. 3 and 4), geared at its ends to the shafts 128. The pitch of the lifting screw 126 is such that it and the lifting worms 129 are driven at the proper rate so that the arm or frame 88 may be fed up and down with an equal and parallel movement of all its parts. The lifting screw 126 and the vertical shafts 128 are connected together to be actuated concurrently by intermediary 95 connections comprising a vertical-adjusting shaft 132 (Figs. 1, 2 and 3), a short upright intermediate shaft 133, and a horizontal connecting shaft 134, the adjusting shaft 132 being geared to the lifting screw 126, the shafts 132, 133, and 134 being geared together, and the connecting shaft 134 being geared to the transverse shaft 131, as shown in the drawings. By rotating the vertical-adjusting shaft 132, the height of the tool carriage 52 above the platen 1 may be adjusted, the direction of the screw threads of the lifting screw 126 and of the worms 129 being such as to operate in harmony to raise or lower the arm or frame 88. 110

The vertical-adjusting shaft 132 is connected with the cross-shaft 119 so as to be rotated thereby in either direction, while the cross-shaft 119 rotates in one or in an unchanged direction. The connecting means 115 between these two shafts is shown as a belt 135 passing over a long belt pulley 136 carried by the cross-shaft 119 and is adapted to engage any one of three pulleys 137, 138 and 139 on the adjusting shaft 132, according as the latter shaft is to be driven in one direction or the other or remain at rest, and the belt may be shifted by a belt-shifting slide 140 of ordinary form. The outer or end pulley 137 is loose on the shaft 132 and, therefore, when the belt is on this pulley, the lifting mechanism is not actuated. The pulley 138 is fixed on the shaft 132, and when the belt is shifted to this pulley the shaft 132 is driven directly in the same di- 130

rection of rotation as the cross-shaft 119. The pulley 139 is loose on the shaft 132, but is geared thereto by a train of bevel gears, 141, 142, and 143, the gear 141 being carried by the pulley 139 and the gear 143 being fixed on the shaft 132 while the gear 142 is an idler or intermediary transmitting gear. When the belt is on the pulley 139, as illustrated in the drawings, it is evident that the direction of rotation of the shaft 132 is opposite to that above noted. By disconnecting the work-feeding clutch 32 and the tool-feeding and tool-driving clutch 115, the vertical-adjustment just described may be accomplished singly, without actuating any other parts of the machine.

In the modification illustrated in Fig. 12, the tool carriage 52 is provided with a planer head 144 which is adapted for carrying a planing tool 145. To install the planer head 144 the shaft hanger 56 and the bearing 65 and their adjuncts, including the grinder 53, are removed from the carriage 52 and the planer-head substituted. The carriage 52 may be fed along the arm or frame 88 by the feed screw 89 in the same manner as above described. Adjusting devices of ordinary form are provided as indicated, for adjusting the planing tool 145 relatively to the carriage 52. In operation the planing tool 145 and the work may be fed the one relatively to the other by feeding the carriage 52, by feeding the work-supporting platen 1, or by feeding both the carriage and the platen as desired while the tool 145 engages the work.

By the various feeds and adjustments of the machine stones may be shaped to a great variety of forms or configurations. A stone 40 may be shaped to an oval or substantially elliptical form, as in Fig. 13, by imparting a swinging feed movement to the tool carriage, while the work-supporting platen is stationary, to form one of the longer curves, 45 then rotating the platen while the carriage is stationary to form a shorter curve and then reversing the position of the platen and repeating these operations to form the remaining longer and shorter curves. Also 50 a stone could be shaped to substantially this form by rotating the platen and feeding it (by feeding the table) transversely at the same time to form the longer curves. It is evident that a hole or opening of the form 55 indicated in this figure, or of other shape, can be formed or dressed out with equal facility. An arched stone, such as illustrated in Fig. 14, may be formed by cutting a plane or radial end thereof with the jointing saw, 60 then shaping the arched surface with the grinder, either by rotating the platen or by swinging the arm, or by doing both at once, and then cutting the other plane radial end with the jointing saw. There is no limit 65 to the arc of curve that may be dressed or

faced as it may be anything from a point to a straight line. The shorter curves are made by merely rotating the platen and the longer curves are made as resultants of rotating the platen and swinging the arm, it being possible thus to describe a longer curve than would result from swinging the arm alone. The ability of the machine to describe these very long curves is particularly useful in dressing metal. An ogee curve in 70 a cornice stone, as illustrated in Fig. 15, may be formed by feeding the carriage along the ways and reversing the direction of rotational feed of the table during the operation. Also this result may be accomplished by 80 swinging the arm and reversing the direction of the rotational feed of the table. It is obvious that a great variety of other forms may be shaped and that innumerable variations of these forms may be produced, 85 including combinations of straight and curved lines of varied arc of curvature. It is also obvious that the rates of the various feeding movements the one to another may be changed or varied in the well known manner of changing the gears so as to vary the relative sizes of the gears by which the feeds are actuated. It is further obvious that any kind of material that is capable of being 90 planed or ground may be acted upon by this 95 machine.

It is obvious that various modifications may be made in the constructions shown and above particularly described within the principle and scope of my invention. 100

I claim:

1. A stone shaping machine comprising a support, a horizontally swinging arm pivoted on the support and provided with ways, a horizontal arcuate guide for supporting the swinging end of the arm, means for simultaneously vertically adjusting the arm and the guide, and a tool-supporting carriage movable on the ways. 105

2. A stone shaping machine comprising a support, a horizontally swinging arm pivoted on the support and provided with ways, a horizontal arcuate guide for supporting the swinging end of the arm, means for simultaneously vertically adjusting the arm and the guide, a tool-supporting carriage movable on the ways, a shaft hanger mounted and vertically adjustable on the carriage, a shaft journaled in the hanger so as to be vertically adjustable therewith, a rotary tool mounted on the shaft, means for imparting a swinging feed movement to the arm, and means for feeding the carriage along the ways. 110

3. A stone shaping machine comprising a 125 bed provided with ways, a table movable on the ways, a work-supporting platen rotatably mounted on the table, a support, a horizontally swinging arm pivoted on the support and provided with ways, a tool-sup- 130

- porting carriage movable on the ways, means for feeding the table along the ways, means for rotatively feeding the platen on the table, means for imparting a swinging feed movement to the arm, means for feeding the carriage along the ways, independent means for actuating the different feeding means, and means in common for concurrently actuating such independent means.

10. 4. A stone shaping machine comprising a bed provided with ways, a table movable on the ways, a work-supporting platen rotatably mounted on the table, a support, a horizontally swinging arm pivoted on the support and provided with ways, a tool-supporting carriage movable on the ways, means for feeding the table along the ways, means for rotatively feeding the platen on the table, means for imparting a swinging feed movement to the arm, means for feeding the carriage along the ways, and mechanism for independently or concurrently actuating the different feeding means.

15. 5. A stone shaping machine comprising a bed provided with ways, a table movable on the ways, a work-supporting platen rotatably mounted on the table, a support, a horizontally swinging arm pivoted on the support and provided with ways, a tool-supporting carriage movable on the ways, means for feeding the table along the ways, means for rotatively feeding the platen on the table, means for imparting a swinging feed movement to the arm, means for feeding the carriage along the ways, and mechanism for independently or concurrently actuating the different feeding means.

20. 6. A stone shaping machine comprising a bed provided with ways, a table movable on the ways, a work-supporting platen rotatably mounted on the table, a support, a horizontally swinging arm pivoted on the support and provided with ways, a tool-supporting carriage movable on the ways, a shaft hanger mounted and vertically adjustable on the carriage, a shaft journaled in the hanger so as to be vertically adjustable therewith, a rotary tool mounted on the shaft, means for feeding the table along the ways, means for rotatively feeding the platen on the table, means for imparting a swinging feed movement to the arm, means for feeding the carriage along the ways, independent means for actuating the different feeding means, and means in common for concurrently actuating such independent means.

25. 7. A stone shaping machine comprising a bed provided with ways, a table movable on the ways, a work-supporting platen rotatably mounted on the table, a support, a horizontally swinging arm pivoted on the support and provided with ways, a tool-supporting carriage movable on the ways, a shaft hanger mounted and vertically adjustable on the carriage, a shaft journaled in the hanger so as to be vertically adjustable therewith, a rotary tool mounted on the shaft, means for feeding the table along the ways, means for rotatively feeding the platen on the table, means for imparting a swinging feed movement to the arm, means for feeding the carriage along the ways, and mechanism for independently or concurrently actuating the different feeding means.

30. 8. A stone shaping machine comprising a work support, a tool carrier, means for imparting a rectilinear feed movement to the work support, means for imparting a curvilinear feed movement to the work support, means for imparting a rectilinear feed movement to the tool carrier, means for imparting a curvilinear feed movement to the tool carrier, the feed movements of the work support and of the tool carrier being in parallel planes and the rectilinear movements being also in planes at an angle one to another and perpendicular to the parallel planes, and means for independently or concurrently actuating the different feeding means.

35. 9. A stone shaping machine comprising a work support, a tool carrier, means for imparting a rectilinear feed movement to the work support, means for imparting a curvilinear feed movement to the work support, means for imparting a rectilinear feed movement to the tool carrier, means for imparting a curvilinear feed movement to the tool carrier, the feed movements of the work support and of the tool carrier being in parallel planes, and means for independently or concurrently actuating the different feeding means.

40. 10. A stone shaping machine comprising a work support, a tool carrier, means for imparting a rectilinear feed movement to the work support, means for imparting a curvilinear feed movement to the tool carrier, the feed movements of the work support and of the tool carrier being in parallel planes, and means for independently or concurrently actuating the different feeding means.

45. 11. A stone shaping machine comprising a work support, a tool carrier, means for imparting a rectilinear feed movement to the work support, means for imparting a curvilinear feed movement to the tool carrier, the feed movements of the work support and of the tool carrier being in parallel planes, and means for independently or concurrently actuating the different feeding means.

50. 12. A stone shaping machine comprising a work support, a tool carrier, means for imparting a rectilinear feed movement to the work support, means for imparting a curvilinear feed movement to the tool carrier, the feed movements of the work support and of the tool carrier being in parallel planes, and means for independently or concurrently actuating the different feeding means.

55. 13. A stone shaping machine comprising a work support, a tool carrier, means for imparting a rectilinear feed movement to the work support, means for imparting a curvilinear feed movement to the tool carrier, the feed movements of the work support and of the tool carrier being in parallel planes, and means for independently or concurrently actuating the different feeding means.

60. 14. A stone shaping machine comprising a work support, a tool carrier, means for imparting a rectilinear feed movement to the work support, means for imparting a curvilinear feed movement to the tool carrier, the feed movements of the work support and of the tool carrier being in parallel planes, and means for independently or concurrently actuating the different feeding means.

65. 15. A stone shaping machine comprising a work support, a tool carrier, means for imparting a rectilinear feed movement to the work support, means for imparting a curvilinear feed movement to the tool carrier, the feed movements of the work support and of the tool carrier being in parallel planes, and means for independently or concurrently actuating the different feeding means.

currently actuating the different feeding means, whereby the different feed movements may be combined to produce resultant feed movement or may take place singly as 5 desired.

22. A stone shaping machine comprising a work support, a tool carrier, means for imparting a rectilinear feed movement to the work support, means for imparting a rectilinear feed movement to the tool carrier, 10 means for imparting a rotational feed movement to one of these members relatively to the other, the feed movements of the work support and of the tool carrier being in parallel planes and the rectilinear movements being also in planes at an angle one to another and perpendicular to the parallel planes, and means for independently or 15 concurrently actuating the different feeding 20 means.

23. A stone shaping machine comprising a support, a swinging arm pivoted on the support, and a jointing saw mounted on the swinging arm with one of its faces in the 25 same plane as the axis of the pivot of the swinging arm.

24. A stone shaping machine comprising a support, a swinging arm pivoted on the 25

support and provided with ways, a tool-supporting carriage movable on the ways, and a jointing saw mounted on the carriage with one of its faces in the same plane as 30 the axis of the pivot of the swinging arm.

25. A stone shaping machine comprising a support, a horizontally swinging arm pivoted on the support and provided with ways, a tool-supporting carriage movable on the ways, a hanger mounted and vertically adjustable on the carriage, and a jointing saw journaled on the hanger and with one of its faces in the same plane as the 35 40 axis of the pivot of the swinging arm.

26. A stone shaping machine comprising a support, a swinging arm pivoted on the support, a jointing saw carried by the 45 swinging arm, and means for interchangeably bringing either face of the saw into the same plane as the axis of the pivot of the swinging arm.

In testimony whereof I affix my signature 50 in presence of two witnesses.

WILLARD F. MEYERS.
